TO DINGS ELECTRO-MAGNETIC SEPARATOR CO., OF MILWAUKEE, WISCONSIN, A
CORPORATION OF WISCONSIN.

MAGNETIC SEPARATOR.

1,209,269.

Specification of Letters Patent. Patented Dec. 19, 1916.

Application filed August 11, 1911. Serial No. 843,504.

To all whom it may concern:

Be it known that we, MYRON DINGS and ROBERT A. MANEGOLD, citizens of the United States, residing at Milwaukee, county of Milwaukee, and State of Wisconsin, have invented new and useful Improvements in Magnetic Separators, of which the following is a specification.

Our invention relates to improvements in magnetic separators.

The object of our invention is to provide a form of construction in which the number of parts and the cost of construction is reduced to the minimum, regard being had 15 for durability and efficiency.

In the following description, reference is had to the accompanying drawing, which illustrates a side elevation of our improved separator, with parts broken away to better 20 show the features of construction.

In the drawing, a set of electro-magnetic coils A, A, is illustrated, each of said coils being provided with the ordinary core piece B. Each core piece is provided with a polar 25 projection C. These polar projections extend horizontally, each in the direction of the other, and are preferably provided with flat upper surfaces over which shaking feed plates D extend, as clearly shown at the left 30 hand side in the drawing. These shaking plates are provided with feeding projections d. These projections d preferably have the form of transverse ribs, and the outer side of each rib is inclined, while the inner side 35 has an abrupt or vertical face, whereby, when said plates are reciprocated longitudinally, the material is progressively shifted from one projection over the next by inertia, and thus fed inwardly toward the inner margin 40 of the plate. The plates are reciprocated from any suitable source of power by any ordinary mechanism.

In the drawing, a driving belt E operates pulley E' on a shaft e. This shaft is provided with a pulley e', through which motion is transmitted through the belt F and pulley f to a shaft f', centrally located above the machine. From this shaft f', motion is transmitted to the left hand shaking plate

through a pulley G, belt g, pulley g', shaft H, and an eccentric H', operatively connected with the plate. The motion of the right hand shaking plate D may be derived directly from the shaft e through an eccentric (not shown), but understood to be similar to the eccentric H' at the left hand side. A carrier I of magnetizable material is employed to remove the magnetite laterally from the shaking plates D. This carrier I comprises a solid metallic disk supported by a vertical shaft J to rotate horizontally over the inner end portions of the shaking plates D. It preferably has screw threaded engagement with the shaft J and is normally locked in position by a set screw K, which may, however, be loosened from time to time, to permit an adjustment of the disk I into greater or less proximity to the shaking plates according to the requirements of the work. The shaft J is provided with a supporting collar L, bearing upon a frame member L', and said shaft J is driven from the cross shaft f', through the beveled gear wheels M and N.

The disk carrier I is provided with a series of projections O on its under surface and in proximity to its outer margin, these projections preferably comprising annular depending ribs having comparatively sharp edges. The carrier I is of greater diameter than the width of the plates D. It is inductively magnetized from the pole pieces C, while passing over the plates D, and therefore carries the magnetite laterally from the plates D. It will be understood that any given portion of the carrier in passing from one of the pole pieces C to the other, traverses a neutral zone extending transversely of the carrier between the pole pieces, the polarity changing upon crossing this zone. We therefore provide a segmental receiver P on each side of the inner portions of the plates D, adapted to collect materials carried by the carrier laterally from such plates, the material and the carrier being demagnetized in crossing the neutral zone, and the material being thereafter permitted to drop into the receivers P. These receivers are preferably

provided with inclined bottom portions leading to a chute Q, through which the magnetite is discharged to any suitable point of delivery. The non-magnetizable materials 5 on the shaking plates D are fed progressively inwardly and permitted to drop in the space between the electro-magnetic coils below the inner margins of said plates.

The vertical position of our magnets enables us to not only build separators in small units with large magnet coils due to the upright position, but this fact and also the use of reciprocating conveyers and a solid disk shaped induction magnet enables us to build 10 a machine which is adapted for high intensity work, whereby we are enabled to treat feebly magnetic material.

In constructing machines in accordance with our invention, the length of the magnet 20 and the diameter can be varied at will without making the machine clumsy. Further, we are enabled to utilize both pole pieces of the magnet, since both legs project upwardly and these pole pieces being 25 of opposite polarity, it is obvious that the lines of force will be caused to thread diametrically through the induction wheel above the conveyers, the only gaps being those occupied by the comparatively thin 30 vibratory or oscillatory conveyer plates. This enables us to reduce the air gap between the magnet poles and the induction wheel or armature to less than one-half inch, and owing to the fact that large coils may be 35 employed in proportion to the size of the machine and both legs of the magnet utilized with lines of force passing almost directly across from one pole to the other through the horizontally rotating solid armature 40 with the air gaps reduced to a minimum, it will be obvious that we are able to produce a separator of great power in proportion to its size.

Having thus described our invention, what 45 we claim as new, and desire to secure by Letters Patent, is—

1. The combination with a set of vertically disposed electromagnetic coils having polar projections of opposite polarity at 50 their upper ends, a horizontally rotating solid disk of magnetizable material having its outer portions located above said pole pieces and adapted to form a straight path for magnetic lines of force extending directly across from the space above one pole 55 piece to the space above the other, means for rotating said disk and having means for feeding material containing magnetite through the gap between the pole pieces and 60 said disk, said conveying means comprising a thin support for the material having but one thickness in the supporting member, whereby the dimensions of the air gaps are reduced to a minimum and a magnetic sepa-

rator of high intensity produced in which 65 the solid rotating disk forms an induced magnet rotating in close proximity to the pole pieces.

2. The combination with an electromagnet having a set of electromagnetic coils 70 with vertical axes and inwardly projecting pole pieces, a vibratory non-magnetizable conveyer extending inwardly above each pole piece and adapted to deliver material to the spaces between the magnets, a horizontally rotatable solid disk of magnetizable material located immediately above and spanning the pole pieces, with the inner portions of the conveyers interposed, said disk having a diameter greater than the width 80 of the conveyers and constituting an induced magnet in a single magnetic field, which extends from one pole piece to the other through the disk and cuts the conveyers above each pole piece, each of said conveyers comprising a vibratory plate, means for reciprocating said plates, and a set of ribs on each plate extending transversely to the line of reciprocatory movement and having inclined outer surfaces and abrupt inner surfaces, whereby the material will be progressively shifted inwardly by said plates, substantially as described.

3. A magnetic separator, comprising the combination with an electromagnet having an upwardly projecting pole piece, of a vibratory conveyer plate projecting inwardly over said pole piece, means for imparting reciprocal vibrations to said plate, a horizontally rotatable solid disk of magnetizable material having a portion thereof located immediately above the inner end portions of said plate and having a diameter greater than the width of the plate, and a set of conveying ribs on said plate having inclined outer surfaces and abrupt inner surfaces, substantially as described.

4. The combination with a set of electromagnetic polar projections of opposite polarity at their upper ends, a horizontally 110 rotating solid disk of magnetizable material having its outer portions located above said pole pieces and adapted to form a straight path for magnetic lines of force extending directly across from the space above one pole 115 piece to the space above the other, means for rotating said disk and means for feeding material containing magnetite through the gap between the pole pieces and said disk, said conveying means comprising a 120 thin support for the material, whereby the dimensions of the air gaps are reduced to a minimum and a magnetic separator of high intensity produced in which the solid rotating disk forms an induced magnet rotating in close proximity to the pole pieces.

5. Means for separating ore comprising means for establishing a magnetic circuit

having magnetic gaps, said circuit including a rotatable disk and a magnet core having each of its pole faces opposing the member to form the gaps, said disk forming a flux travel path between the gaps, and means for positioning the ore material within the gaps.

In testimony whereof we affix our signatures in the presence of two witnesses.

MYRON DINGS.

ROBERT A. MANEGOLD.
